US00D582977S

(12) **United States Design Patent**
Field et al.

(10) **Patent No.:** **US D582,977 S**
(45) **Date of Patent:** **** Dec. 16, 2008**

(54) **TRANSACTION DEVICE**

(75) Inventors: **Manning R. Field**, Media, PA (US);
Walter Brent Reinhard, Lansdale, PA (US)

(73) Assignee: **JPMorgan Chase Bank, N.A.**, New York, NY (US)

(**) Term: **14 Years**

(21) Appl. No.: **29/303,976**

(22) Filed: **Feb. 21, 2008**

(51) **LOC (8) Cl.** **19-08**

(52) **U.S. Cl.** **D19/10**

(58) **Field of Classification Search** D19/1-34; 40/124.01-124.15, 672, 726; 283/72, 74, 283/75, 103, 105, 106; 206/449; D21/385; D20/10, 22, 27, 40, 42, 11; D14/435-437

See application file for complete search history.

(57) **CLAIM**

We claim the ornamental design for a transaction device, as shown and described.

DESCRIPTION

FIG. 1 depicts a perspective view of a transaction device.

FIG. 2 depicts a front elevation view thereof;

FIG. 3 depicts a rear elevation view thereof;

FIG. 4 depicts a right-side elevation view thereof;

FIG. 5 depicts a left-side elevation view thereof;

FIG. 6 depicts a top plan view thereof; and,

FIG. 7 depicts a bottom plan view thereof.
